PRIMARY SUCTION DRUM ASSEMBLY

Roy H. Breyfogle, Alton, Ill., assignor to Alton
Box Board Company, Alton, Ill., a corporation
of Delaware

Application June 6, 1947, Serial No. 752,863

4 Claims. (Cl. 92—43)

1

This invention relates to an assembly for strengthening newly formed wet delicate paper webs so that the same can be handled without damage.

Specifically the invention deals with a suction drum arrangement for cylinder type paper making machines wherein the pick-up felt of the machine is extended longitudinally beyond the last cylinder mold and has a suction press positioned to act on the run of the pick-up felt between this last cylinder mold and the point where the felt is turned.

This invention will be hereinafter specifically described as embodied in a suction drum arrangement for cylinder type paper making machines, but is not limited to such a preferred embodiment. For example, the forming part of the machine can be widely varied without departing from the principles of this invention.

According to this invention the pick-up felt of a cylinder type paper making machine is extended in the machine direction so as to have a horizontal run beyond the last cylinder mold. The felt is trained around a turning roll at the end of this run and passes upwardly around a suction drum to extend therefrom in a horizontal direction above the machine. A feature of this invention resides in the provision of a primary suction drum press to act on a pick-up felt along the horizontal run thereof beyond the last cylinder mold. This primary suction drum press extracts sufficient moisture from the web on the pick-up felt so that the web is considerably strengthened and can be directed around a turning roll without damage. The web is preferably covered with a covering felt also trained through the primary suction drum press and around the suction roll that is positioned above the turning roll. The covering felt continues with the web along the run of the pick-up felt above the machine. A suction transfer roll is provided at the point of separation of the covering felt and pick-up felt to maintain the web on the pick-up felt.

It is, then, an object of this invention to provide a paper making machine with a primary suction drum press to act on the freshly made fragile paper web before the direction of travel of the web is changed.

Another object of the invention is to provide a paper making machine with a primary suction drum assembly acting on the freshly made paper web immediately after the web leaves the forming surface and before it is subjected to a change in direction of travel.

A specific object of the invention is to provide a cylinder type paper making machine with an

extended pick-up felt run beyond the last cylinder mold, and to interpose a primary suction drum press along this run of the felt.

Another object of the invention is to provide a pick-up felt arrangement for paper making machines with a plurality of suction presses so arranged as to strengthen the web on the felt without damage to enable the web to be handled at high speeds.

A still further object of the invention is to provide a pick-up felt arrangement with a covering felt and suction rolls to strengthen the web of paper conveyed by the felts while it is between the pick-up felt and the covering felt.

Other and further objects of the invention will be apparent to those skilled in the art from the following detailed description of the annexed sheet of drawings which, by way of a preferred example only, illustrates one embodiment of the invention.

On the drawing the figure is a fragmentary diagrammatic elevational view of a cylinder type paper making machine equipped with a primary suction drum assembly according to this invention.

As shown on the drawing, the reference numeral 10 designates a cylinder type paper making machine having a plurality of cylinder vats 11 each containing a cylinder mold 12. A couch roll 13 coacts with each cylinder mold 12. A pick-up felt 14 has a lower horizontal run over the tops of the cylinder molds 12 and through the nips between the cylinder molds and their coacting couch rolls 13. A pick-up felt 14 thus receives, on its under face, a web from each cylinder mold 12, and the composite web W produced by the machine is carried on the under face of the felt 14.

The bottom horizontal run of the pick-up felt 14 extends horizontally beyond the last cylinder vat 11 to a turning roll 15. The turning roll receives the felt around the under face thereof and provides an extended horizontal run for the felt and web beyond the last cylinder vat. A suction press 16 is provided to act on this extended run of the pick-up felt 14. The press 16 includes a plain top press roll 17 and a suction roll 18 in pressure nip relationship therewith. The suction roll 18 has a suction area 19 extending into the nip from a point in advance of the nip.

The pick-up felt 14 extends upwardly around the turning roll 15 to a suction drum 20 and passes around this drum over the suction area 21 thereof and under a cooperating top press roll 22. A second suction press 23 is thus provided by the rolls 20 and 22. Having thus made a 180°

3

turn in two stages about rolls 15 and 20, the felt 14 passes through the nip of this second press 23 in a horizontal direction and travels rearwardly through a plain press roll assembly 24 to a third suction press 25. The plain press 24 is composed of a pair of wringer rolls including a bottom roll 26 and a top roll 27. Alternately, these rolls 26 and 27 can function merely as guide rolls.

The third suction press 25 includes a bottom suction roll 28 and a coacting plain top press roll 29. The suction area 30 of the press 25 extends from the nip of the press to a point forward of the nip.

After passing through the third suction press 25, the pick-up felt 14 is guided rearwardly in a horizontal direction over the top of the machine 10 by means of guide rolls 31.

A covering felt 32 is provided to cover the web W as it passes through all three presses 16, 23, and 25. The felt 32 is endless, and a turning roll 33 in the loop thereof directs the felt onto the suction roll 18 of the first suction press 16 to travel thereon over the suction area 19 thereof and into contact with the web W. The felt 32 thus covers the web W as it passes through the nip of the first suction press, and the web, between the pick-up felt and the covering felt 32, then extends around the turning roll 15 and through the nip of the second suction press 23. After leaving the second suction press 23, the web, while still between the two felts 14 and 32, passes through the nip of the plain press 24 and through the nip of the third suction press 25. After passage through the nip of the third suction press 25, a turning roll 34 also within the loop of the felt 32 directs the felt upwardly away from the pick-up felt 14. The suction area 30 of the third press 25 is effective to retain the web on the pick-up felt so that the covering felt 32 is separated from the web. An inside guide roll 35 directs the felt 32 from the turning roll 34 along a horizontal run above the presses 24 and 25 to a tensioning roll 36 which coacts with an external roll 37 in maintaining the felt 32 in a taut condition. The felt travels from the external roll 37 to an internal turning roll 38 and travels downwardly therefrom over a guide roll 39 which holds this run of the felt outwardly from the upward run of the pick-up felt. A beater 40 acts on the covering felt 32 as it passes between the guide roll 39 and a turning roll 41. The felt travels from the turning roll 41 over guide rolls 42 and 43 in a horizontal direction beneath the first suction press 16.

The first or primary suction drum assembly press 16 sufficiently dewateres the fragile freshly formed composite web W so that it can be turned around the turning roll 15 without damage. The press 16 acts on the web before the web is subjected to any change in direction of travel. It removes a relatively high percentage of water from the paper, and the paper, with its reduced water content, is sufficiently strengthened so that the change in direction can be made more easily and safely. Only a half of the direction change occurs before the web is subjected to its second dewatering treatment by the press 23. The second half of the change of direction takes place as the web passes through this second press 23.

From the above description it will be understood that this invention provides an assembly which efficiently dewateres freshly made fragile paper webs before these webs are subjected to stresses. The dewatering sufficiently strengthens

the webs so that they can thereafter be subjected to stresses such as occur when their direction of travel is changed.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A cylinder type paper making machine comprising a cylinder mold web forming section, a pick-up felt trained over said section and having a lower horizontal pick-up run and an upper horizontal return run, a turning roll at the end of said lower run spaced longitudinally from the end of the forming section to provide a lower run portion beyond the forming section, a suction press assembly having a suction roll receiving therearound the pick-up felt from said turning roll to complete the change of direction of travel of the felt between the lower and upper runs, a second suction press having a suction roll and receiving said upper run of the pick-up felt therethrough, the suction roll of said second suction press contacting said pick-up felt, a primary suction press between said forming section and said turning roll, said primary suction press having a suction roll, and a covering felt trained through all three of said suction presses for covering the web on the pick-up felt continuously from the time it enters the nip of the primary suction press until it leaves the nip of the second suction press, said primary suction press receiving the extended lower run of the pick-up felt therethrough, the suction roll of said primary suction press contacting the covering felt.

2. In a cylinder type paper making machine wherein a web is deposited from a cylinder mold directly upon a pick-up felt and transported about substantially a 180° turn in two stages and in contiguous relation with a covering felt and the pick-up felt, the combination of a primary suction press ahead of the turn arranged to exert its suction on the covering felt to tend to pull the web from the pick-up felt toward the covering felt, and a second suction press beyond the turn arranged to exert its suction on the pick-up felt to tend to pull the web from the covering felt toward the pick-up felt.

3. In a cylinder type paper making machine wherein a web is deposited from a cylinder mold directly upon a pick-up felt and transported about a turn in contiguous relation with a covering felt and the pick-up felt, the combination of a primary suction press ahead of the turn, said primary suction press having a suction element on the side of the web which is contiguous with the covering felt, and a second suction press beyond the turn, said second suction press having a suction element on that side of the web which is contiguous with the pick-up felt, said suction elements being in direct contact with the felts respectively.

4. In a cylinder type paper making machine wherein a web is deposited from a cylinder mold directly upon a pick-up felt and transported beyond said cylinder mold in contiguous relation with said pick-up felt, the combination comprising a plurality of suction presses arranged respectively to receive and operate upon the web while on said pick-up felt at substantially spaced stations beyond the cylinder mold, each of said suction presses having a suction element and a

press roll between which said pick-up felt and web pass, a covering felt mounted to travel in contiguous relation with the web on said pick-up felt through said plurality of suction presses, the suction element on the one of said presses nearest said cylinder mold being on the covering felt side of said web, and the suction element of another of said presses being on the pick-up felt side of said web, whereby the suction presses press the felts together and apply unidirectional suction thereto first toward the covering felt side and subsequently toward the pick-up felt side without separating either felt from the intervening web.
